HOLDER FOR POOL AND BILLIARD CUES

Russell G. Gardner, 2645 Valley Ave.,
Winchester, Va. 22601

Filed Feb. 7, 1975, Ser. No. 548,069

Term of patent 14 years

Int. Cl. D21—01

U.S. Cl. D34—3

Fig. 1

Fig. 2

FIG. 1 is a perspective view of a holder for pool and billiard cues showing my new design.

FIG. 2 is a view which is similar to that of FIG. 1 but which illustrates a modification.

The sides not shown are substantially the same as those shown.

I claim:

The ornamental design for holder for pool and billiard cues, as shown and described.
